HARRY W. EHRLEN, OF BELLEVUE, AND JAMES H. MATTHEWS, OF PITTSBURGH, PENNSYLVANIA, ASSIGNORS TO JAS. H. MATTHEWS & COMPANY, OF PITTSBURGH, PENNSYLVANIA, A CORPORATION OF PENNSYLVANIA.

FOUNTAIN INKING ROLL.

Application filed March 11, 1927. Serial No. 174,464.

Our invention relates to fountain inking rolls, such as are used in printing apparatus of various sorts; and it consists in an inking roll containing within itself an ink reservoir, from which reservoir ink is automatically supplied to the roll, that it may serve its intended purposes, and yet the roll, by virtue of our invention, possess this characteristic: When at rest it is free of the undesirable seepage of ink from the reservoir to and through the roll surface.

A roll embodying the invention is shown in the accompanying drawings. Fig. I is a view of the roll partly in side elevation, 15 partly in axial section; Fig. II is a view in end elevation.

The roll includes a shell of impervious material, ordinarily of metal, faced with felt. To hollow cylindrical roll body 1, the 20 heads 2 are one or both of them adjustably secured, as by the screw-thread connection 10. The space within constitutes an ink reservoir. The heads 2 are of greater diameter than the body 1, and they present opposite faces 20, between which opposite faces a body of felt, advantageously built of a series of rings 3, encircling the body 1, is by the application of and adjustment of the removable head or heads, securely clamped. 25 The body 1 is perforate, that the ink within 30 the reservoir may while the roll continues in service have access automatically to the felt face of the roll. This body of felt soaks up the ink so supplied to it. Its consistency is 35 such that the ink is thus available on its surface in sufficient quantity to meet the conditions and the needs of service. The preparation of the ink and the provision of ink having proper physical characteristics 40 are matters within the knowledge of those who use such apparatus.

In the heads of the roll externally we have shown axial conical recesses 24. These recesses are intended to receive conical bearing 45 spindles, on which the roll may turn. In this respect the particular roll shown is exemplary merely. All that concerns us is to show that the invention is practicable upon a roll adapted for rotation, that it may in 50 service perform its intended office.

The perforations 30 through the body 3 are not found throughout all the circumferential extent of the shell like body 3; they are found throughout a portion only of the

circumferential extent of the cylinder and 55 advantageously throughout half the circumferential extent,—to one side only of an axial plane. Throughout so much of the extent of the cylinder as may be desired, and as here shown throughout the imperforate 60 portion of the cylinder, to the other side of that axial plane, superficial grooves 31 extend. These grooves extend transversely and are here advantageously shown to extend semi-circumferentially, from one perforation 65 30 to another, and they preferably extend helically upon the cylindrical surface. By virtue of the fact that the body 3 is throughout half its cylindrical extent imperforate, it is adapted when in proper position to contain without escape and without 70 consequent seepage through the felt, a body of ink which fills the reservoir less than half full. By virtue of the fact that the body 3 throughout this half of its extent is grooved externally, the ink issuing 75 when the roll is in rotation through perforations 30 is distributed beneath the felt throughout all the cylindrical extent of the roll body and the whole of the felt facing 80 of the roll is properly and adequately supplied with ink.

A filling hole closed by a removable plug 21 may be formed at a convenient place; here it is shown to be formed in one head of the cylinder. And the head may bear indication, such as the arrow 22 or the line 23 or both, that the user may know when the roll is in position with the perforations 30 all above the horizontal axial plane, and with 85 the grooves 31 entirely beneath the horizontal axial plane. We have said entirely above and entirely beneath the axial plane, whereas Fig. II of the drawings shows the extreme perforations 30 centered in a diameter of the cylinder, so that, accurately speaking, by the diameter of one perforation, the perforate area exceeds a half cylinder. But the purport and meaning of the 90 description will, with allowance for this, be understood. It will be perceived that the head which bears these indicia might be integral with or otherwise positively fixed in its position relatively to the cylinder body; but if it be united to the cylinder body by 95 screw-thread engagement, as shown, then when screwed to position upon body 1, the 100 relative positions of these two parts for

service must be carefully established, so that the indicia referred to shall occupy proper rotational position relatively to the perforate and the grooved portions of body 1.

5. The roll is for all purposes of operation maintained on a horizontal axis. The filling hole is preferably drilled through the head in such position that when the assembly is completed it shall lie on the same side of the cylinder with perforations 30 and on the side opposite to grooves 31. This relative position is indicated in Fig. II. When the assembly has so been made plug 21 may be removed and through the hole ink may be introduced into the reservoir within, in quantity to fill the reservoir not more than half full. The plug 21 may then be replaced. The roll may then be rotated and used and ink will be supplied through the felt facing after the usual manner.

At times when the roll is to remain idle—at night, or at other times of inaction—it is carefully placed in the position indicated in Fig. II, with the perforations 30 all above the horizontal axial plane and the imperforate part of the cylinder entirely below the horizontal axial plane. So long as the roll

rests in that position the ink within the reservoir will rest in an imperforate half cylindrical trough and there will be no undesired seepage and escape of ink. Rotation again reestablishes normal feed of ink.

The preferred composite formation of the body of felt, as a series of rings, and the presence beneath the body of felt of the spaces which the grooves afford, are features which make for a freer and better feeding of the ink to the roll surface.

We claim as our invention:

An inking roll consisting of a cylindrical body of impervious material provided with a superficial facing of pervious material, the cylindrical body to one side of an axial plane affording an imperforate semi-cylindrical ink trough, the cylindrical body in such portion being provided on its outer surface with transversely extending grooves, and the cylindrical body to the other side of such axial plane being provided with ink conducting perforations.

In testimony whereof we have hereunto set our hands.

HARRY W. EHRLEN.
JAMES H. MATTHEWS.
